HANDLE FOR PORTABLE POWER TOOLS OR THE LIKE

Bernard A. Swanson, 11805 SE. 54th Place,
Bellevue, Wash. 98004

Filed Oct. 21, 1968, Ser. No. 14,092

Term of patent 14 years

Int. Cl. D8—02

U.S. Cl. D8—107

Fig. 1.

Fig. 2.

Fig. 4.

Fig. 3.

FIG. 1 is an isometric view of the handle;
FIG. 2 is a side view;
FIG. 3 is a top plan view; and
FIG. 4 is an end view of the tool handle.
The dominant features of my design reside in the portions shown in full lines.

I claim:

The ornamental design for a handle for portable power tools or the like, as shown and described.
